UNITED STATES PATENT OFFICE.

JOHN GLASNER, OF ESTILL SPRINGS, TENNESSEE, ASSIGNOR OF ONE-HALF TO J. K. WILLIAMS, OF FAYETTEVILLE, TENNESSEE.

LOAD LOCKING AND RELEASING MEANS FOR OVERHEAD CARRIERS.

Application filed May 17, 1922. Serial No. 561,680.

To all whom it may concern:

Be it known that I, JOHN GLASNER, a citizen of the United States, residing at Estill Springs, in the county of Franklin and State 5 of Tennessee, have invented a new and useful Load Locking and Releasing Means for Overhead Carriers, of which the following is a specification.

This invention relates to load locking and 10 releasing means designed primarily for use with overhead carriers such as employed in logging, etc.

One of the objects of the invention is to provide a simple and compact arrangement 15 of parts whereby, through the actuation of the various cables connected to the carrier, a load can be raised, secured so as to be supported directly from the carrier, conveyed to a point of delivery, and then released.

20 The invention is of substantially the same type as that disclosed in my co-pending application filed August 15, 1921, Serial No. 492,626.

With the foregoing and other objects in 25 view which will appear as the description proceeds, the invention resides in the combination and arrangement of parts and in the details of construction hereinafter described and claimed, it being understood 30 that, within the scope of what is claimed, changes in the precise embodiment of the invention shown can be made without departing from the spirit of the invention.

In the accompanying drawings the preferred form of the invention has been 35 shown.

In said drawings

Figure 1 is a side elevation of the carrier.

40 Figure 2 is an end elevation thereof.

Referring to the figures by characters of reference 1 designates a supporting cable or sky line constituting the support for the grooved wheels 2 of the carriage 3 through 45 which the cable 1 extends. The carriage includes side plates 4 between which the wheels 2 are mounted, and supported between and by these plates is a lever 5 fulcrumed at its upper end, as shown at 6 while its lower end is formed with a forked hook 7. A bar 8 is pivotally connected to the upper portion of the lever and is mounted to slide between guides 9 arranged between the plates 4. An out haul line 10 is connected to the bar 8. A releasing line 11 is

connected to the lever 5 and is supported between the plates 4 by a guide sheave 12. Another sheave 13 is supported between the lower portions of the plates 4 and mounted on this sheave is a load line 14 having a 60 knob or enlargement 15 thereon.

In Figure 1 the lever 5 and its hook 7 have been shown in two positions. When the carriage is moved outwardly for loading, the out haul line 10 serves to pull the 65 carriage along the cable 1. During this operation the lever 5 is of course positioned as shown by broken lines in Figure 1. After the carriage arrives at the position where the load is to be taken on the releasing line 11 70 is tightened so as to pull the lever 5 and hook 7 back to the position shown by full lines in Figure 1. Thus the hook 7 is supported out of the path of the knob or enlargement 15 and the load line 14 can be operated 75 so as to lift the load and bring the knob or enlargement 15 above the path of the hook 7. The releasing line 11 is then slackened so as to allow the lever 5 to swing toward its normal position. This will bring 80 the forked hook 7 astride the load line 14 at a point below the knob or enlargement 15. Then by slightly lowering the load line the knob or enlargement 15 will rest on the forked hook 7 and the lever 5, as shown in 85 Figure 1, will support the entire weight of the load and thus relieve the upper portion of the load line 14. The carriage can then be brought into the place of unloading by operating the load line and the releasing 90 line, which of course are actuated by the drums at the skidder machine employed. When the load reaches the point of unloading the out haul line is held fast by the foot 95 brake; then the load line and releasing lines 95 are tightened slightly and this operation will raise the load sufficient to permit the releasing line, which is also drawn forward, to pull the hook 7 out of the path of the knob or enlargement to the position indicated 100 by full lines in Figure 1 and by slackening the load line the knob or enlargement 15 will pass downwardly below the hook 7 and the load will be permitted to descend to the ground.

105 What is claimed is:-

1. In an overhead carrier a carriage, a load line suspended therefrom, a load line engaging member movably connected to the carriage, means on the load line for engag- 110

2
ing said member to support a load, and oppositely extending out haul and releasing lines connected to said member for moving the member into and out of load line engaging position.

2. In an overhead carrier a carriage, a lever fulcrumed thereon, a load line suspended from the carriage, a knob or enlargement thereon, a locking line connected to the lever and an out haul line connected to said lever, said locking line and out haul line operating to swing the lever in opposite directions respectively relative to the carriage.

3. In an overhead carrier a carriage, a load line suspended therefrom, a knob or enlargement upon the load line, a lever pivotally connected to the carriage, a hook extending therefrom, said load line being supported for engagement by the hook, an out haul line for shifting the carriage, and a locking line connected to the lever for shifting

the lever out of its normal load-line-engaging position and moving the carriage in one direction.

4. In an overhead carrier a sky line, a carriage movable therealong, a load line depending from the carriage, a load line engaging member movably connected to the carriage, means on the load line for engaging said member to support a load, and a line separate from the load line and operable independently of the movement of the carriage relative to the sky line, for shifting the said member relative to the load line.

In testimony that I claim the foregoing as my own, I have hereto affixed my signature in the presence of two witnesses.

JOHN GLASNER.

Witnesses:

GEO. MOSELEY,
JACOB WENGER.
